United States Patent Office

Des. 212,332
Patented Oct. 1, 1968

212,332

CARD READER

Christopher Kingsley Brown, Camp Hill, Pa., assignor to AMP Incorporated, Harrisburg, Pa.

Filed Mar. 21, 1966, Ser. No. 1,571

Term of patent 14 years

(Cl. D26—5)

Fig. 1

Fig. 2

I claim:

The ornamental design for a card reader, substantially as shown.
